UNITED STATES PATENT OFFICE.

JOHN S. PITNER, OF MIDWAY, PENNSYLVANIA.

DESIGN FOR A TOOL-HANDLE.

SPECIFICATION forming part of Design No. 30,407, dated March 28, 1899.

Application filed February 3, 1899. Serial No. 704,425. Term of patent 7 years.

To all whom it may concern:

Be it known that I, JOHN S. PITNER, a citizen of the United States, residing at Midway, in the county of Washington and State of Pennsylvania, have invented and produced a new and original Design for a Tool-Handle; and I do hereby declare the following to be a full, clear, and exact description of the invention, such as will enable others skilled in the art to which it appertains to make and use the same.

In the drawings, Figure 1 is a perspective view of the tool-handle. Fig. 2 is a longitudinal section through the handle.

As shown in the drawings, the leading or material feature of the design is an externally-rounded handle which is bifurcated, being provided with a slot or opening extending from the upper end of the handle, longitudinally thereof, to nearly the lower end thereof, said slot extending through the sides and upper end of the handle but not through its lower end, and two rectangular portions or lugs arranged at the top of the handle and provided with holes extending crosswise through the handle near its upper end at right angles to the said slot, one hole being ar-

ranged on each side of the center line of the handle.

A is the handle, which is rounded externally so that it can be grasped comfortably by the hand.

B is the slot, which extends from the upper end of the handle nearly to its lower end and which is open at the sides and top.

C C are grooves arranged longitudinally at the center part of the handle in the said slot.

D D are the two holes, extending crosswise through the handle near its upper end and one on each side of its center.

E E are projecting lugs on the upper part of the handle around the said holes.

The handle is hollow, and the slot B has enlargements b at its lower part at the sides of the handle.

What I claim is—

The design for a tool-handle, as herein shown and described.

In testimony whereof I affix my signature in presence of two witnesses.

JOHN S. PITNER.
